CLAIM

The ornamental design for a pull tab, as shown and described.

DESCRIPTION

FIG. 1 is a top plan view of a pull tab showing our new design.

FIG. 2 is a bottom plan view thereof.

FIG. 3 is a right side elevational view thereof, the left side view being a mirror image thereof;

FIG. 4 is a front end elevational view thereof;

FIG. 5 is a rear end elevational view thereof;

FIG. 6 is a fragmentary cross-sectional view thereof, taken on line 6—6 of FIG. 1;

FIG. 7 is a fragmentary cross-sectional view taken along line 7—7 of FIG. 1; and

FIG. 8 is a fragmentary cross-sectional view thereof taken along line 8—8 of FIG. 1.

FIG. 1

FIG. 2

FIG. 3

FIG. 4

FIG. 5

FIG. 6

FIG. 7

FIG. 8
